UNITED STATES PATENT OFFICE.

HERMAN GILLIAN, OF COLUMBUS, OHIO.

WORK GLOVE.

Application filed March 1, 1926. Serial No. 91,405.

This invention relates to gloves of cloth and wear facing material, as leather.

This invention has utility when incorporated in work gloves lined with fabric and 5 faced at the wear portions with fragments of leather.

Referring to the drawings:

Fig. 1 is a front view, with parts broken away, of a glove of the invention herein;

10 Fig. 2 is a section on the line II—II, Fig. 1;

Fig. 3 is a section on the line III—III, Fig. 1;

15 Fig. 4 is a fragmentary view of the back of the glove of Fig. 1;

Fig. 5 is a section on the line V—V, Fig. 1;

20 Fig. 6 is a view of the palm extension blank facing wristward;

Fig. 7 is a view of the lining blank;

Fig. 8 is a view of the palm facing blank;

Fig. 9 is a view of the thumb back facing;

25 Fig. 10 is a view of a fractional fourchette facing blank;

Fig. 11 is a view of the little finger back tip facing blank; and

Fig. 12 is a view of an intermediate finger back tip facing blank.

30 Palm lining 1 is shown as having integral therewith back 2 and also digit linings 3, 4, 5, 6, 7, 8, 9, 10, integral therewith. Accordingly, there is provided a seamless hand back, as well as seamless hand front lining blank independent of seams between the

35 digits and such hand back and front portions. There is assembled on this lining, blank palm facing 11 having integral therewith digits 12, 13, 14, 15, 16, 17. Stitching 18 assembles the thumb portions 3, 12, 19,

40 together with the lining similar to the facing 19. Stitching 20 assembles the index finger back 17 with the lining back 2 as the lining digit 7 is folded and base fourchette 21 has its edge 22 assembled with edge 23 of

45 the index finger back facing 17 by seam 24, which seam is checked on this fractional fourchette 21 to start at the projection 25. From projection 26, finger tip back 27 is

50 connected by seam 28. Similar assembly is effected of these fractional fourchettes and finger tips in completing the assembly with

little finger tip blank facing 29 assembled with the little finger front facing 13. With the fragments and general palm facing thus assembled with the lining unit, closing 55 seam 30, from the tip of the index finger, may serve to tack or catch the extremities of the lining 7 together; the linings 6, 8; the linings 5, 9; the linings 4, 10, with the lining extending to the crotch portions of 60 such digits not assembled together by this closing seam 30, which closing seam 30 may extend about the fingers and down the little finger side to gauntlet 31. The front portion of this gauntlet 31 is connected to the 65 palm facing 11 with gauntlet facing 32.

In the glove of this disclosure, there is flexibility with full protection for the wear portions of the finger backs together with fourchette reinforcement between the fingers. 70 These fractional fourchettes, extending to but an intermediate point of the fingers, as well as the tip portions, also extending short of the finger back, permit the use of fragments of the facing material, as leather, 75 which means that in practice trim portions from the palms, which may normally be waste, are thus utilized, and there is practically no additional expense for material. Furthermore, due to this seamless or unitary lining, there is notwithstanding such facing, a reduction in the total sewing required with a degree of flexibility retained in the glove for ease on the hand of a workman with wear facing and lining at the 80 points to give the glove life.

What is claimed and it is desired to secure by United States Letters Patent is:

A glove lining unit having integral front, back and digit portions, a palm facing 90 having integral digit fronts, facing fourchettes at the finger crotches connected to the finger front facing to terminate intermediate of the length of the fingers, and facing finger back tips connected to the finger 95 front facing and extending away from the tips of the fingers to the fourchettes and short of extending to the region of the finger crotches.

In witness whereof I affix my signature.

HERMAN GILLIAN.
